UNITED STATES PATENT OFFICE.

HARRY S. DICKINSON, OF MOLINE, ILLINOIS, ASSIGNOR TO MOLINE PLOW COMPANY, A CORPORATION OF ILLINOIS.

LISTER-CULTIVATOR.

1,271,292.

Specification of Letters Patent.

Patented July 2, 1918.

Application filed June 27, 1916, Serial No. 106,090. Renewed May 15, 1918. Serial No. 234,779.

To all whom it may concern:

Be it known that I, HARRY S. DICKINSON, a citizen of the United States, residing at Moline, in the county of Rock Island and 5 State of Illinois, have invented certain new and useful Improvements in Lister-Cultivators, of which the following is a specification, reference being had therein to the accompanying drawing.

10 This invention relates to cultivators and has reference more particularly to lister cultivators in which cultivating devices carried by the frame of the machine operate between adjacent ridges at opposite sides of 15 the row of plants. Machines of this type are usually sustained by a pair of carrying wheels which are set so as to run in rather close proximity to the row on opposite sides of the same, and these wheels are adjustable 20 up and down in order to raise the cultivating devices out of action when turning at the ends of the rows or in transporting the machine. Owing to the comparative close 25 proximity of the carrying wheels to each other, the machine is liable to tip, more particularly when turning at the ends of the rows or in transportation, and to meet this condition it is customary to provide a pair 30 of balance wheels which are mounted out- 35 ward of the carrying wheels and which are adjustable up and down so that when the machine is in action the balance wheels will travel on the ridges between which the carrying wheels run, and when the machine 40 is out of action as when turning or in transporting, the balance wheels are moved down so as to travel at the same level as the carrying wheels. It is also customary to arrange 45 the balance wheels so that they may be set 50 to travel at different elevations with reference to the carrying wheels in order to meet the varying conditions encountered in practice as to the height of the ridges.

By reason of the arrangement of the 55 parts mentioned, when the machine is in operation on the plants, the two sets of wheels travel at different levels, the balance wheels at a higher elevation than the carrying wheels, and in raising the frame and 60 cultivating devices at the ends of the rows, the two sets of wheels are moved downwardly relatively to the frame so as to occupy the same level, the balance wheels in 65 this operation being compelled to move a greater vertical distance than the carrying 70 wheels; and when the wheels are moved upwardly to again lower the frame and cultivating devices for action, the balance wheels are moved a greater vertical distance upwardly so as to occupy a higher level. 75 Various forms of mechanisms for controlling these movements of the two sets of wheels have been devised, but so far as I am aware these mechanisms have been of a complicated character, and it has been necessary in moving the two sets of wheels from a different level to the same level or vice versa, to actuate separate adjusting mechanisms for the respective sets. 80 The aim of my invention is to simplify this mechanism for controlling the movements of the two sets of wheels and the invention consists broadly in operative connections between the two sets of wheels so constructed and arranged that the wheels 85 will be caused to move together in lowering them to raise the frame or in raising them to lower the frame, but different relative vertical distances, the balance wheels moving a greater distance than the carrying wheels, 90 whereby when the wheels are lowered the balance wheels will move from a higher level to the same level as the carrying wheels, and when the wheels are raised the reverse movement of the balance wheels will take place. 95 In the more specific embodiment of my invention, a single operating lever for controlling the movements of the two sets of wheels is employed, and two connecting devices from the lever to the respective sets of 100 wheels are provided, these parts being so arranged relatively that when the lever is operated to lower the wheels in order to raise the machine out of action, the two sets of wheels will move together, the balance wheels a greater vertical distance than the supporting wheels, and when the lever is operated to raise the wheels and lower the machine into action, the two sets of wheels will again move together with the balance 105 wheels moving a greater distance upwardly than the carrying wheels so that they will occupy a higher level to travel on the ridges. My invention also consists in so forming the operative connections between the two sets of wheels that the position of the balance wheels relative to the carrying wheels may be varied or adjusted, to the end that the varying conditions encountered in practice as regards the height of the ridges on 110

which the balance wheels travel may be provided for.

In the accompanying drawings:

Figure 1 is a perspective view of a lister 5 cultivator having my invention embodied therein.

Fig. 1^a is a fragmentary sectional view of a portion of the hand lever and connected parts.

10 Fig. 2 is a rear view in the nature of a diagram showing the relative positions of the carrying wheels and the balance wheels with the latter traveling on the ridges and the former traveling between the ridges at 15 the sides of the row of plants.

Fig. 3 is a side elevation of the machine with the parts in the position they occupy when the cultivating devices are down in action.

20 Fig. 4 is a similar view showing the wheels down and the cultivating devices elevated out of action.

Referring to the drawings:

1 represents the frame of the machine to 25 which is attached a stub tongue 2. Mounted on the frame is a horizontal transverse rock shaft 3 pivoted to the frame by means of horizontal transverse pivot bolts 3^a to rock about the axes of the bolts. The shaft is 30 provided with an upwardly extending arm 4, and has adjustably connected with it a transverse rear frame member 1^a. Jointed to this arm is the rear end of a link 5 which extends forwardly and has its forward end 35 jointed as at 6 to an upright hand lever 7, the lower end of which is pivoted to the stub tongue on a horizontal transverse axis as at 8. The lever is provided with a locking latch not shown but adapted to engage a 40 toothed segment frame 10 fixed to the stub tongue and operated by a latch lever 7^a on the lever 7 by means of which lever the rock shaft 3 may be rocked in the frame and held fixedly in its different positions.

45 9, 9 represent two carrying-wheel supports in the form of stems fixed at their upper ends to the rock shaft and extending downwardly therefrom, the said stems being bent outwardly at their lower ends to form axles 50 for carrying wheels 11. The stems 9 are set rather close together near the center of the rock shaft so that the carrying wheels will travel in close proximity to the sides of the row of plants as shown in Fig. 2, and when 55 the machine is in operation with the cultivating devices in action, the carrying wheel stems 9 will extend at a forward inclination as shown in Fig. 3, the lever 7 when the wheels are in this position, being in its rear 60 position, as shown in Fig. 3. When the lever is swung forwardly to the position shown in Fig. 4 the shaft 3 will be rocked in a clockwise direction which will swing the carrying wheel stems 9 rearwardly and will elevate 65 the frame of the machine.

The cultivating devices in the present instance are in the form of cultivating shovels 12 sustained by the frame member 1^a and cultivating disks 12^a carried on the rear ends of beams 13 which extend forwardly and upwardly and have their forward ends fixed to the rock shaft 3, so that when the wheel stems are swung to the rear to raise the frame, these disks will be raised from the ground, the effect of the rearward movement 75 of the carrying wheels being in this action to counter-balance the weight of the disks by shifting the center of gravity of the machine in the manner well known to those skilled in this art.

Journalized in bearings 14 on the frame in advance of the rock shaft 3 is a second horizontal transverse rock shaft 15, the ends of which are extended downwardly to form balance wheel supports or stems 16, the lower ends of these stems being turned outwardly to form axles 17 on which balance wheels 18 are mounted.

These balance wheels are disposed outwardly of and a considerable distance from the carrying wheels, and when the machine is in action they are adapted to travel at a higher level than the carrying wheels and on the tops of the ridges as shown in Fig. 2. When the machine is turned at the ends of 85 the rows or is to be transported these balance wheels are moved downwardly so as to travel at the same level as the carrying wheels as shown in Fig. 4, the function of 90 the wheels being thus to maintain the machine frame horizontal and prevent the same from tipping which would be liable to occur from the fact that the carrying wheels are set close together at the center of the machine.

Firmly fixed to and extending upwardly from the rock shaft 15 is an arm 19 containing a number of latch engaging openings 20 arranged in a row at different distances from the axis of the shaft, the said arm being curved for the purpose presently to be described. These latch openings are adapted to be engaged by a latch 21 on the rear end of a link 22 which link extends forwardly to the hand lever 7 and passes 110 loosely at its forward end through a block 23 which is pivoted to the hand lever on a horizontal transverse axis coincident with the point of pivotal connection of the link 5 with the said lever. The link 22 extends 115 beyond the block and is provided on its extremity with an adjustable head 24 between which and the forward side of the block the link is encircled by a spiral spring 25.

As a result of the construction described, when the lever 7 is pushed forwardly it will, due to its connection with the arm 19 by the link 22, rock the shaft 15 in a clockwise direction which action will swing the balance wheel stems 16 rearwardly and will 120 125 130

lower the wheels from an elevated position as shown in Fig. 3 to the position shown in Fig. 4, the movement of the lever in the opposite direction causing a reverse motion 5 of the parts and elevating the balance wheels from a lowered position as shown in Fig. 4 to an elevated position as shown in Fig. 3, it being understood that in these movements of the balance wheels, the carrying wheels will 10 be simultaneously moved due to the connection of the hand lever with the rock shaft 3.

The arm 19 is curved from a center coincident with the pivotal point of connection of the block 23 with the hand lever when the 15 balance wheels are in their lowered position, as shown in Fig. 4, the result being that when the parts are in this position with both sets of wheels traveling at the same level, the link 22 may by means of the latch 21 thereon 20 be connected with the arm 19 at different distances from the axis of the shaft 15. The purpose of this construction is to enable the balance wheel stems to be moved, for a given movement of the carrying wheel stems, a 25 greater vertical distance, so that the balance wheels, when the machine is lowered into action, will be moved upwardly and assume a higher level than the carrying wheels so as to travel on the ridges, and when the machine 30 is raised out of action the balance wheels will be moved downwardly to the same level as the carrying wheels, these movements of the balance wheels being greater in extent in a vertical direction than the corresponding movements of the carrying wheels. 35 The link 22 is shown connected with the arm 19 at a point closer to the axis of the shaft 15 than the distance between the axis of shaft 3 and the point of connection of the link 5 with the arm 4, the result being that 40 the balance wheels will be given a greater movement in the operation of the hand lever, than the movement of the carrying wheel, the latch being shown as engaged in the lowest 45 of the series of latch openings.

It is seen therefore that with the parts adjusted in the position shown, the two sets of wheels will when the hand lever is operated, be moved together, but the balance wheels 50 will be moved a greater distance than the carrying wheels and will always assume the same level when moved downwardly to elevate the frame for transportation or turning and the two sets of wheels will always assume 55 different levels when moved upwardly to lower the frame for action.

By the engagement of the latch in one or the other of the openings above the lowest one, the effective leverage of the arm 19 on 60 the rock shaft 15 will be increased, with the result that the proportionate relative movement of the two sets of wheels will be decreased. Such adjustment of the latch would be resorted to in cases where the ridges on 65 which the balance wheels travel when the

machine is in action, were less in height than those shown, such conditions requiring a lesser degree of movement of the balance wheels in relation to the carrying wheels when moving from an elevated position to a 70 lowered position or vice versa. It is seen therefore that by reason of the adjustable connection of the link 22 with the arm 19, the relation of the balance wheels to the carrying wheels may be changed, in order to 75 meet the changing conditions encountered in practice as regards the height of the ridges on which the balance wheels travel, the operation of the lever 7 however causing the balance wheels when moved downwardly to elevate the frame to always take the same level as the carrying wheels without regard to what particular adjustment the balance wheels may have been set with reference to the carrying wheels. 80

From the foregoing description it will be seen that the driver by means of the single controlling hand lever is enabled to instantly and automatically control the movements of both sets of wheels, notwithstanding the fact 85 that in their movements, one set of wheels moves a different vertical distance from the other set.

In the accompanying drawings and foregoing description I have disclosed my invention in the particular form and detailed construction which I prefer to adopt, but it will be understood that various changes may be made in these details, and that the construction may be variously modified without departing from the limits of my invention provided the operation is substantially as above set forth; and it will be further understood that the invention is not limited to any particular form or construction of the parts except in so far as such limitations are specified in the claims. 95

I lay no claim in the present application to those features which are shown and claimed in my companion application filed 100 January 21st, 1916, Ser. No. 73,290.

Having thus described my invention, what I claim is:

1. In a cultivator, the combination of a frame adapted to carry cultivating devices, carrying wheels mounted on the frame and adapted to travel at the sides of the row and movable up and down relatively to the frame, balance wheels mounted on the frame outward of the carrying wheels and movable 115 up and down relatively to the frame, and means for moving the two sets of wheels together but different relative vertical distances. 120

2. In a cultivator, the combination of a frame adapted to carry cultivating devices, carrying wheels mounted on the frame and adapted to travel at the sides of the row and movable up and down relatively to the frame, balance wheels mounted on the frame 125 130

outward of the carrying wheels and movable up and down relatively to the frame, connections between the two sets of wheels to cause them to move together but different 5 relative vertical distances, and an operating lever sustained by the frame and connected with said connecting devices for operating them.

3. In a cultivator, the combination of a 10 frame adapted to carry cultivating devices, carrying wheels mounted on the frame and adapted to travel at the sides of the row and movable vertically relatively to the frame, balance wheels mounted on the frame 15 outward of the carrying wheels and movable up and down relatively to the frame, and operative connections between the two sets of wheels to cause them to move together different relative vertical distances, 20 said connections being adjustable to vary the relation of the two sets of wheels to each other in the direction of movement.

4. In a cultivator, the combination of a 25 frame adapted to carry cultivating devices, carrying wheels mounted on the frame and adapted to travel at the sides of the row and movable up and down relatively to the frame, balance wheels mounted on the frame outward of the carrying wheels and movable 30 up and down relatively to the frame, and operative connections between the two sets of wheels to cause them to move together, said connections operating when the wheels are down and the frame elevated to 35 maintain the wheels at the same level, and operating when the wheels are up and the frame lowered to maintain the sets of wheels at different levels.

5. In a cultivator, the combination of a 40 frame adapted to carry cultivating devices, carrying wheels mounted on the frame and adapted to travel at the sides of the row and movable up and down relatively to the frame, balance wheels mounted on the frame 45 outward of the carrying wheels and movable up and down relatively to the frame, and means for moving the two sets of wheels together different relative vertical distances, the balance wheels a greater distance than 50 the carrying wheels.

6. In a cultivator, the combination of a 55 frame adapted to carry cultivating devices, carrying wheels mounted on the frame and adapted to travel at the sides of the row and movable up and down relatively to the frame, balance wheels mounted on the frame outward of the carrying wheels and movable up and down relatively to the frame, a common operating member, a connecting device 60 between the operating member and the carrying wheels, and a second connecting device between the operating member and the balance wheels, said parts being so constructed and relatively arranged that the 65 actuation of the operating member will

cause the two sets of wheels to move together but different relative vertical distances.

7. In a cultivator, the combination of a 70 frame adapted to carry cultivating devices, a horizontal transverse rock shaft mounted in the frame, carrying-wheel supports connected with the rock shaft, carrying wheels mounted on the supports and movable up and down in the rocking motions of the 75 shaft, a lateral arm on the shaft, a second horizontal transverse rock shaft mounted in the frame, balance-wheel supports connected with the rock shaft, a lateral arm on said second rock shaft, balance 80 wheels mounted on the balance-wheel supports and movable up and down in the rocking motions of the second rock shaft, an operating lever mounted on the frame, a connecting device jointed at one end to the 85 lever and at its other end to the arm on the first mentioned rock shaft, and a second connecting device jointed at one end to the lever and at its opposite end to the arm on the 90 second mentioned rock shaft, the point of connection of said second mentioned connecting device with its arm being closer to the axis of the second mentioned shaft than is the point of connection of the first mentioned connecting device with its arm to 95 the axis of the first mentioned shaft; whereby both sets of wheels will be caused to move together, the balance wheels a greater vertical distance than the carrying wheels.

8. In a cultivator, the combination of a 100 frame adapted to carry cultivating devices, a horizontal transverse rock shaft mounted in the frame, carrying-wheel supports connected with the rock shaft, carrying wheels mounted on the supports and movable up and down in the rocking motions of the 105 shaft, a lateral arm on the shaft, a second horizontal transverse rock shaft mounted in the frame, balance-wheel supports connected with said second rock shaft, balance wheels mounted on the balance-wheel supports and movable up and down in the rocking motions of the shaft, a lateral arm on said second rock shaft, an operating lever mounted on the frame, a connecting device jointed at one end to the lever and at its other end to the arm on the first mentioned rock shaft, and a second connecting device jointed at one end to the lever and adjustably connected at its other end to the arm on said 110 second rock shaft.

9. In a cultivator, the combination of a 115 frame adapted to carry cultivating devices, a horizontal transverse rock shaft mounted in said frame, carry-wheel supports connected with the rock shaft, carrying wheels mounted on the supports and movable up and down in the rocking motions of the shaft, a lateral arm on said rock shaft, a second horizontal transverse rock shaft 120 125

mounted in the frame, balance-wheel supports connected with said second rock shaft, balance wheels mounted on said supports and movable up and down in the rocking motions of the shaft, a lateral arm on said second rock shaft, an operating lever mounted on the frame, a connecting device pivoted at one end to said lever and at its other end to the arm on the first mentioned 5 rock shaft, a second connecting device pivoted at one end to said lever, and means for jointing the opposite end of the connecting device to the arm on the second rock shaft at different distances from the axis 10 of the shaft.

10. In a cultivator, the combination of a frame adapted to carry cultivating devices, a horizontal transverse rock shaft mounted in the frame, carrying-wheel supports connected with the rock shaft, carrying-wheels mounted on said supports and movable up and down in the rocking motions of the shaft, a lateral arm on said shaft, a second horizontal transverse rock shaft mounted in 20 the frame, balance-wheel supports fixed to said rock shaft, balance wheels mounted on the supports and movable up and down in the rocking motions of the shaft, an operating lever mounted on the frame, a connecting device jointed at one end to the lever and at its opposite end to the arm on the first mentioned rock shaft, a second connecting device pivoted at one end to said operating lever, a lateral arm on the second mentioned rock shaft provided with a series of 25 openings extending in an arc whose axis is coincident with the point of pivotal connection of the second mentioned connecting device with the operating lever when the two 30 sets of wheels are down and the frame elevated, and means for connecting the opposite end of the second connecting device in the different openings in the arm as desired.

11. In a cultivator, the combination of a frame adapted to carry cultivating devices, a horizontal transverse rock shaft mounted in the frame, carrying-wheel supports connected with the rock shaft, carrying wheels mounted on the support and movable up and 45 down with the rocking motions of the shaft, a second horizontal transverse rock shaft mounted in the frame, balance-wheel supports connected to said second rock shaft,

balance wheels mounted on said supports and movable up and down in the rocking 55 motions of the shaft, a lateral arm on the first mentioned rock shaft, an operating lever mounted on the frame, a connecting device between the operating lever and the said lateral arm, a second connecting device 60 jointed at its forward end to the operating lever and extending rearwardly therefrom, and a lateral arm on the said second rock shaft curved in an arc whose center is coincident with the point of pivotal connection 65 of the second connecting device with the operating lever when the two sets of wheels are down and the frame elevated, the second mentioned connecting device being provided with means for locking the same to the 70 curved arm at different distances from the axis of the arm.

12. In a cultivator, the combination of a frame adapted to carry cultivating devices, a horizontal transverse rock shaft mounted 75 in the frame, carrying-wheel supports fixed to the shaft, carrying wheels mounted on the supports and movable up and down in the rocking motions of the shaft, a second horizontal transverse rock shaft mounted in 80 the frame, balance-wheel supports connected with said rock shaft, balance wheels mounted on said supports and movable up and down in the rocking motions of the shaft, a hand lever pivoted to the frame in 85 advance of said shafts and movable back and forth on a horizontal transverse axis, a link pivoted to said lever on a horizontal transverse axis, a locking latch on the rear end of said link, a lateral arm on the second 90 mentioned rock shaft provided with a series of latch engaging openings arranged in a line curved from an arc whose center is coincident with the point of pivotal connection of the link with the lever when two 95 sets of wheels are down and the frame of the machine elevated, said latch openings adapted to be engaged by the latch on said link, a lateral arm on the first mentioned rock shaft, and a link connected at its forward end with the operating lever and at its rear end with said lateral arm.

In testimony whereof I have affixed my signature.

HARRY S. DICKINSON.
